UNITED STATES PATENT OFFICE

CHESTER D. AINSWORTH, OF WOLLASTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS

ELECTRIC-SWITCH-OPERATING MECHANISM

Application filed December 13, 1922. Serial No. 606,678.

This invention relates to electric switches and has particular reference to manually and electrically controlled mechanisms for operating said switches.

5 An object of this invention is to provide an electric switch with operating mechanism including means to lock the switch in closed position and tripping means so arranged as to be controlled by any one or all of a plurality of tripping coils.

10 A further object of the invention is to provide switch operating mechanism arranged for both electrically controlled, automatic operation and manually controlled operation with manually controlled means to effect the opening of the switch at automatic speed, whereby to prevent the switch from being opened slowly.

15 A further object of the invention is to provide the switch operating mechanism with an auxiliary signal switch which may be operated automatically with the main switch and also manually and may be locked in open position.

20 A further object is generally to improve the construction and operation of electric switches and operating mechanisms therefor.

25 Fig. 1 is a side elevation of a face plate for an electric switch bearing the switch operating mechanism embodying the invention.

Fig. 2 is a plan view in section taken along line 2-2 of Fig. 1.

30 Fig. 3 is a vertical sectional detail through the coil box of the face plate.

Fig. 4 is a view similar to Fig. 3 but with certain parts removed to illustrate the method of removing the tripping coils from the coil box.

35 Fig. 5 is a detail illustrating the mechanism for the auxiliary signal switch.

Fig. 6 is a view of the switch operating mechanism associated with an oil switch.

40 As here shown, the switch operating mechanism embodying the invention includes a face plate 10 which is adapted to be mounted upon some suitable vertical support 11 by suitable means as the bolts 12. Said bolts extend through said support 11 and secure to 45 said support a suitable bracket 13 to which a

bell crank lever 14 is pivoted. Said bell crank lever is actuated by the switch operating mechanism to move a rod 15 which is connected in a suitable manner to an electric switch 16, Fig. 6, which is remotely disposed with respect to said face plate. A pair of links 17 are secured in spaced relation to opposite sides of said bell crank lever 14 and extend through apertures in said support 11 and face plate 12 and are pivotally connected with a switch-operating lever 18. The lower portion of said face plate 10 is formed to provide an enclosure or tripping-coil box 19 and the front wall of said coil box is formed or provided with projections 20; and the lower end of said lever 18 is pivotally supported on a pin 21 which is passed through said projections 20. Said lever 18 is adapted to be moved about its pivotal support to effect the opening and closing of the switch. 55 60 65 70

An operating handle 22 is provided by which the switch may be closed manually and, in accordance with this invention, means are provided which are so arranged that said operating-handle can not be manipulated to 75 open the switch manually. Said operating handle includes the spaced bars 23 which are pivotally mounted on the pin 21 on opposite sides of said lever 18. Means are provided by which said lever 18 and consequently the 80 switch operating mechanism are connected releasably with said handle. Said means includes the bracket 25 which is secured to and between said bars 23 of the handle. A tripping latch 24 is pivoted on a pin 25^a carried by 85 said bracket. Said lever 18 is provided with a cam roller 26 rotatably supported at the upper portion thereof and said latch 24 is adapted to engage said cam roller releasably. Said operating handle is adapted to be locked 90 releasably in switch-closed position and said latch 24 is adapted to be actuated both manually and electrically. Said lever 18 and the links 17 connected therewith are adapted to be moved outwardly between the bars 23 of 95 said handle by the weight of the switch mechanism, or pressure of the switch-opening springs, to switch open position. Said operating handle is adapted to be subsequently unlocked and moved towards the left, Fig. 1, to 100

effect the re-engagement of said latch 24 with the lever 18 whereby to permit the switch to be closed manually.

The operating handle locking means includes the latch 30 which is disposed in a slot in the arms 31 which are extended outwardly from the face plate 10; and said latch is pivoted on a pin 32 carried by said arms. Said latch is adapted to engage a projection, 10 as the cam roller 35, of said operating handle and hold said handle in substantially vertical or switch-closed position as shown in Fig. 1, and when moved upward, to release said handle and permit it to be moved outwardly 15 by its own weight, or manually to effect the reengagement of said handle with the lever 18 of the switch operating mechanism. Said handle-locking latch 30 is restricted in its movements by a pin 34 which extends between 20 the arms 31 of said face plate and through an enlarged hole 36 in said latch. Said latch is normally spring pressed into handle holding position by the coil spring 37 and said spring is disposed in the slot between said 25 arms 31 and is supported on a pin 38 connecting said arms. Said spring bears against the bottom wall of said slot and the upper portion of said latch above the pivot pin 32 thereof.

30 The operating mechanism is so arranged that the switch can not be opened by the handle but must be tripped open whereby to release the switch mechanism from the handle and the mechanism is so arranged that the act 35 of tripping the switch member also serves to release the handle-locking latch 30 from holding engagement with the operating handle. For this purpose, said latch 24 is provided with suitable manually-engageable means as 40 the pin 40 which is extended laterally on opposite sides of said latch and is adapted to be engaged by the hand whereby to raise that portion of the latch and cause it to release the lever 18 of the switch operating mechanism whereby to permit the switch to open.

Said latch 24 is arranged to be moved upwardly in the manual switch-opening movement and engage a projection 41 of the handle locking latch 30 and thereby raise said latch 50 and consequently unlock the handle; and said latches are so arranged that the manual unlocking operation also serves to move the handle outwardly, whereby but one hand only need be required to open and close the switch.

55 It is thus seen that the handle can not be conveniently unlocked until the switch has been tripped and the tripping of the switch by the manual raising of the latch causes the switch to open at the same speed that it 60 opens when automatically tripped. This result is highly advantageous in that it prevents a slow opening of the switch and consequently reduces the probability of burning the switch contacts and otherwise causing damage.

The electric switch tripping mechanism comprises a plurality of tripping coils; and the mechanism is so arranged that each trip coil by itself is effective to trip the switch.

As here shown, the coil box 19 of the face 70 plate is of more or less triangular cross section and is adapted to contain three trip coils 45, each of which is contained in a phase of a three phase circuit and acts to trip the switch upon overload in its respective phase 75 or one or more of said coils may be otherwise arranged to control the switch under different circumstances.

Said coil box 19 is so arranged that the coils may be removed and replaced without 80 removing the face plate from its support or otherwise altering the arrangement of the mechanism.

For this purpose, the bottom wall 46 of said face plate is provided with an aperture 47 85 therethrough which is disposed preferably at the apex portion of the coil box; and said aperture is adapted to be at least as great in diameter as said coils 45 whereby to permit entrance of said coils to and their removal 90 from said coil box. Said aperture 47 is normally closed by a plate 48 which is adapted to enter said aperture and be substantially flush with the inner face of the wall 46; and screws 49, or other suitable attaching means, 95 extend through the flange 50 of said plate to the coil box.

Said trip coils 45 include the center tubes, 100 51 upon which the coils are formed and the tubes 52 which are adapted to be loosely received within said tubes 51; and the movable core 52a of the coils are received in said tubes 52.

Said tubes 52 are provided with reduced 105 and threaded upper portions 53 which are adapted to extend into and through openings 54 in the top wall 55 of said coil box. Internal screw threaded standards 56 are threaded on said tubes 52 whereby to secure them removably in position. The lower wall 46 of 110 said coil box and the plate 48 is formed with openings which are aligned with the openings 54 of the top wall of the coil box and said tubes 52 are adapted to be received removably therein.

115 The arrangement is such that when said tubes 52 are secured in position in the coil box with said coils 45 disposed thereabout, said coils are held securely in position against displacement. Said coils may be removed 120 from the coil box by removing said tubes 52 therefrom and removing the cover plate 48, whereupon the coils may be extracted from the coil box through the aperture 47 in the lower wall thereof.

125 The switch tripping means includes a tripping plate 60 of more or less triangular form and each apex of said plate is disposed in operative relation with a tripping coil contained in said coil box. Said plate is formed 130

with the triangularly disposed slots 61 there-in which are located in the apices thereof and the grooved heads 62 of pins 63 are loosely received in said slots. Said pins 63 are 5 slidably supported in the standards 56 and are adapted to extend through said standards into the interior of the tubes 52 of the tripping coils and be engaged by the cores 52^a of said tripping coils and raised vertically 10 whereby to raise said tripping plate 60, and trip the switch. Said pins 63 constitute tri-podal supporting means for said plate and the arrangement of said plate 60 and pins 63 is such that said plate is loosely, yet securely, 15 supported on said pins and may fulcrum about any two thereof, when one or more pins are raised. Said plate 60 is disposed beneath and in operative relation with the latch 24 and is adapted to engage and raise the inner end of said latch when one or more of 20 said coils 45 is effectively energized whereby to effect the tripping of the switch. Preferably, said tripping plate 60 is provided with a spring plate 65. Said spring plate is 25 adapted to engage the latch 24 and may be raised to varying positions above the plate 60 by suitable means, as by the adjusting screw 66, whereby to admit of slight variations of dimensions in the manufacture of 30 the mechanism. Said plate 60 is provided with the apertures 60^a, which are screw-threaded, by which auxiliary apparatus as, for instance, an under voltage release attachment, not shown, may be arranged to control 35 the tripping of the switch, in addition to the tripping coils herein illustrated.

Said latch 24 is bifurcated as by being provided with the spaced extensions 24^a secured to and disposed on opposite sides of the body 40 of said latch. Said latch-extensions are so arranged that the latch is in effective position to be actuated by the tripping plate when the operating handle and lever 18 are being moved towards switch-closed position so that 45 the switch is tripped free from the handle and restored to open position if an overload is present on the circuit controlled by the switch when the contacts thereof are brought into engagement.

50 An auxiliary or signal switch is associated with the operating mechanism whereby to give audible or other signal of the open-circuit condition of the switch. Said auxiliary switch includes the insulated contact members 70 one of which is shown in Fig. 1. Said contact members are mounted on an insulating block 71 which is secured to a supporting member 72; and said supporting member is secured to the support 11 between 55 said support and the bracket 13. A link or rod 73 is disposed between the links or rods 17 of the operating mechanism and said link 73 is provided with a slot 74 in which is disposed the pin 75 which connects said links 17 with 60 the bell crank lever 14. Said link 73 is

formed or provided with a downwardly extended ear 76 which carries an insulated contact member 77 adapted to engage and bridge the fixed contact members 70 of the auxiliary switch whereby to complete the circuit 70 through said auxiliary switch. The inner end of said link 73 is pivotally connected by the pin 78 to a lever 79; and said lever 79 extends upwardly into the slot between said arms 31 of the face plate and is pivotally 75 supported on a pin 80 extended between said arms. A tension spring 81 is connected with the inner end of said arm and one of said standards 56 and thereby serves to draw the outer end of the slot 74 in said link 73 80 against the pin 75 whereby to bias said auxiliary switch toward closed position.

A latch 85 is pivoted to said lever 79 and one end of said latch is adapted to be disposed between the extensions 24^a of the latch 24 25 and lie over or be disposed in operative relation with the tripping plate 60. The other end of said latch is adapted to engage a projection 86 of the face plate. The arrangement of said auxiliary switch operating 90 mechanism is such that the latch 85 is tripped simultaneously with the latch 24 and thereby releases the auxiliary switch operating mechanism for movement conjointly with the movement of the main switch mechanism 95 whereby to close the auxiliary signal circuit when the main switch is open. Said slot 74 in the link 73 is so disposed that when the switch operating mechanism is operated to close the main switch said auxiliary switch 100 mechanism is also actuated to move to open position and the latch 85 serves to lock said mechanism in closed position. With this arrangement the auxiliary signal circuit is controlled simultaneously with the main switch. 105

When however it is desired to leave the main switch in open position, said lever 79 of the auxiliary switch operating mechanism may be operated manually to move the lever 85 into locking engagement with the face 110 plate 10 whereby to maintain open the auxiliary signal circuit.

The structure may be otherwise modified without departing from the spirit of the invention as, for instance, said tripping latch 115 24^a may be replaced by a toggle.

I claim:

1. Electric switch operating mechanism comprising a normally vertical, pivoted switch-operating lever, a switch operating 120 rod connected thereto, a normally vertical operating handle disposed about said lever, a tripping latch carried by said handle arranged normally to connect said lever with said handle in switch closed position and to 125 release said lever to permit said lever and rod to move through said handle to switch-open position, electro-magnetic tripping means for said tripping latch, and locking means for the handle disposed and arranged 130.

normally to release the handle only after the switch has been tripped open.

2. Electric switch operating mechanism comprising a face-plate adapted for vertical mounting, a switch-operating lever pivoted to the lower end of said face-plate and extended upwardly above its pivot, an operating handle pivoted to said face-plate concentrically with said switch operating lever, a latch carried by said handle and arranged normally to lock said switch-operating lever to said handle, a second latch disposed above said first latch and arranged to lock said operating handle releasably to said face-plate, and electrically-actuated tripping means for said first latch only disposed beneath said first latch.

3. Electric switch operating mechanism comprising an operating handle, a switch operating member, a latch arranged releasably to lock said handle in switch-closed position, a manually operable tripping latch carried by said handle arranged releasably to engage said operating member and connect it with said handle and constructed and arranged, when tripped manually, to operate said handle-locking latch, and electrically-actuated tripping means for said tripping latch.

4. Electric switch operating mechanism comprising an operating handle, a switch operating member, means arranged to connect said handle and member releasably, and independent means arranged releasably to lock said handle in switch-closed position, said connecting means arranged to operate said handle-locking means and release the lock on said handle.

5. Electric switch operating mechanism comprising an operating handle, a switch operating member, means arranged to connect said handle and member releasably, independent means arranged releasably to lock said handle in switch-closed position, said connecting means also arranged to be operated manually and operate said handle locking means and release the lock on said handle, and electrically-actuated means arranged to operate said connecting means only.

6. Electric switch operating mechanism comprising an operating handle, means to lock said handle releasably in switch-closed position and means arranged electrically to effect the opening of the switch without movement of said handle, said second means also arranged manually to open the switch and unlock said handle.

7. Electric switch operating mechanism comprising an operating handle, a switch operating member, a tripping latch carried by said handle arranged releasably to engage said operating member, a latch arranged to hold said handle releasably in switch-closed position regardless of the position of said switch operating member, said handle-hold-

ing latch arranged normally to be tripped only by manual operation of said tripping latch, and a spring arranged yieldingly to urge said handle-holding latch in handle-engaging position.

8. Electric switch operating mechanism comprising a switch-operating member, holding means for said operating member, a tripping member for said holding member having a plurality of angularly-related fulcrum supports characterized by permitting said tripping member to oscillate in any one of a plurality of different vertical planes, and a tripping device arranged to actuate said tripping member and cause it to fulcrum about certain of its supports.

9. Electric switch operating mechanism comprising a switch operating member, holding means for said operating member, a tripping member for said holding member having a plurality of fulcrum supports characterized by permitting said tripping member to oscillate in any one of a plurality of different vertical planes, and a tripping device arranged to actuate one of said supports whereby to fulcrum said tripping member about others of said fulcrum supports and trip said holding means.

10. Electric switch operating mechanism comprising a switch operating member, holding means for said operating member, a tripping member for said holding member having a plurality of fulcrum supports characterized by permitting said tripping member to oscillate in any one of a plurality of different vertical planes, and a plurality of tripping devices each arranged to actuate a fulcrum support, whereby to actuate said tripping member and trip said holding means.

11. Electric switch operating mechanism comprising a switch-operating member, holding means for said operating member, a tripping member for said holding member having a plurality of angularly-related supports about any two of which said tripping member is adapted to fulcrum, and a plurality of tripping devices each arranged to actuate a different fulcrum support, whereby to actuate said tripping member and trip said holding means.

12. Electric switch operating mechanism comprising a switch operating member, holding means for said operating member, a tripping member for said holding member having a plurality of angularly-related supports about any two of which said tripping member is adapted to fulcrum, and a plurality of tripping coils each adapted to be independently energized and to actuate a different support, whereby to actuate said tripping member and trip said holding means.

13. Electric switch operating mechanism comprising a switch operating member, holding means for said operating member, a tripping member for said holding member com-

- prising a plate having a plurality of fulcrum-support engaging means, a plurality of fulcrum-supports arranged in loose engagement with said engaging means, at least one of said supports being movable, and a tripping device arranged to move said movable fulcrum-support, whereby to actuate said plate and trip said holding means.
14. Electric switch operating mechanism comprising a switch-operating member, holding means for said operating member, a tripping member for said holding member comprising a plate having a plurality of angularly-related fulcrum-support engaging means, a plurality of movable fulcrum-supports arranged in loose engagement with said engaging means, and a tripping coil for each fulcrum-support, each coil arranged independently to actuate its fulcrum-support, whereby to actuate said plate and trip said holding means.
15. Electric switch operating mechanism comprising a switch-operating member, holding means for said operating member, a tripping plate adapted to trip said holding means, said plate having triangularly-arranged fulcrum-support engaging means, triangularly-disposed fulcrum-supports arranged in engagement with said engaging means and about any two of which said plate is adapted to fulcrum, and a tripping device arranged to raise one of said fulcrum supports, whereby to raise said plate and trip holding means.
16. Electric switch operating mechanism comprising a switch-operating member, holding means for said operating member, a tripping member adapted to trip said holding means, supporting means for said tripping member, and actuating means for said tripping member including means to raise said member bodily off and also to tilt it on said supporting member, whereby to trip said holding means.
17. Electric switch operating mechanism comprising a switch-operating member, holding means for said operating mechanism, a tripping member for said holding means comprising a plate, supporting means for said plate, and actuating means for said plate, said supporting and actuating means arranged to raise said plate bodily off and also to tilt said plate angularly on said supporting means, whereby to trip said holding means.
18. Electric switch operating mechanism comprising a switch-operating member, holding means for said operating member, a tripping plate adapted to trip said holding means, said plate having triangularly-arranged fulcrum-support engaging slots, triangularly-disposed fulcrum-supports disposed loosely in said slots in supporting relation with said plate, said plate adapted to fulcrum about any two of said supports, and a tripping device arranged to raise one of said
- fulcrum-supports whereby to tilt said plate about said other fulcrum-supports and trip said holding means.
19. Electric switch operating mechanism comprising a switch-operating member, holding means for said operating member, a tripping plate adapted to trip said holding means, said plate having triangularly-arranged fulcrum-support engaging slots, triangularly-disposed fulcrum-supports disposed loosely in said slots in supporting relation with said plate, said plate adapted to fulcrum about any of said supports, and a plurality of tripping devices each arranged to raise a fulcrum-support, whereby to raise said plate and trip said holding means.
20. Electric switch operating mechanism comprising a switch-operating member, holding means for said operating member, a tripping plate adapted to trip said holding means, said plate having triangularly-arranged fulcrum-support engaging slots, triangularly-disposed movable fulcrum-supports disposed loosely in said slots in supporting relation with said plate and about any two of which supports said plate is adapted to fulcrum, said supports also arranged conjointly to hold said plate against disengagement therewith, and a plurality of tripping coils having movable cores arranged to raise said supports, whereby to actuate said plate and trip said holding means.
21. Electric switch-operating mechanism comprising a switch-operating member, holding means for said member, a plurality of triangularly-disposed tripping coils having movable cores, a tripping plate disposed above said coils and adapted to be actuated and trip said holding means, said plate having triangularly disposed slots therein, and triangularly-disposed movable fulcrum supports received loosely in said slots and arranged conjointly to support said plate movably and hold it against detachment therefrom, said cores of said tripping coils arranged to actuate said supports and raise said plate, whereby to trip said holding means.
22. Electric switch operating mechanism comprising a switch-operating member, holding means for said member comprising a latch, a coil box disposed below said latch, a plurality of tripping coils disposed in triangular order in said box, standards carried by said box above said coils, fulcrum-supports comprising rods slidably received in said standards and extended into said coils, a tripping plate adapted to engage and trip said latch, said plate having triangularly-disposed slots therein in which said rods are received and by which said plate is supported for bodily upward movement and also for angular movement about any two rods, and cores movably disposed in said tripping coils arranged to raise said support, whereby to actuate said tripping plate.

23. Electric switch operating mechanism comprising a tripping latch, and a tripping plate adapted to be actuated to trip said latch, said plate having a latch-engaging member comprising a resilient member, and means to adjust the position of said resilient member relative to said latch.

24. Electric switch operating mechanism comprising a pivoted switch-operating lever, a pivoted handle movable between switch open and closed positions, a latch carried by said handle adapted releasably to engage said lever, and a tripping device for said latch, said latch having a projection adapted to be disposed in operative relation with said tripping device in intermediate positions of said handle.

25. The combination of separate operating members for two switches, tripping latches associated with said members, one of said latches having a bifurcated extension and said other latch disposed within the ramifications thereof, and a tripping device common to and arranged to actuate said latches simultaneously.

26. The combination of a main switch and an auxiliary switch, means simultaneously to close and open the main switch and open and close the auxiliary switch in the order named, and means including a lost motion connection between said switches to permit one of said switches to open independently of said other switch.

27. The combination of a main switch, an auxiliary switch biased toward closed position, means simultaneously to open and close the main switch and close and open the auxiliary switch, means to open said auxiliary switch independently of said main switch, and means to lock said auxiliary switch open.

28. The combination of a main switch, an auxiliary switch biased toward closed position, means releasably to hold said auxiliary switch against such movement, and means governed by said main switch to govern the operation of said auxiliary switch.

29. The combination of a main switch, an auxiliary switch biased toward closed position, and means governed by said main switch to govern the operation of said auxiliary switch, and manually controlled means to lock said auxiliary switch open.

30. The combination of a lever, substantially parallel main and auxiliary switch-operating rods pivotally connected with said lever, said auxiliary switch-operating rod having lost-motion connection with said lever, operating handles connected with said rods, latches for holding said rods in set position, and a single tripping member for said latches.

31. Electric switch operating mechanism comprising the combination of a plate formed to provide a box adapted to contain tripping coils, a lever pivoted to the front wall of said

box and extended thereabove, a pair of spaced switch-operating rods pivoted to said lever and extended through said plate, a slotted operating rod for an auxiliary switch disposed between said spaced rods, said plate having an arm extended outwardly above said coil box, a depending handle pivoted to said arm and connected to said slotted rod, a latch carried by said handle above said slotted rod arranged to engage said plate whereby to lock said slotted rod releasably in set position, a switch operating handle pivoted to said coil box and disposed on opposite sides of said lever, a tripping latch carried by said handle arranged to engage and lock said lever releasably to said operating handle, a latch carried by the arm of said plate arranged to engage said operating handle and lock it releasably in switch-closed position, said latch having means by which it is operated by said tripping latch, a tripping plate disposed beneath said tripping latch and the latch governing said slotted rod and arranged to actuate both, tripodod supporting means for said tripping plate, and tripping coils carried in said coil box arranged to actuate said supporting means and thereby actuate said plate to trip said tripping and governing latches.

32. The combination of a main switch and an auxiliary switch, manually-operable for closing and opening the main switch, electrically-operated means for opening the main switch, said auxiliary switch having operating means by which it is opened when the main switch is closed manually, and is restrained against closing while the main switch is in closed position and also when the main switch is opened manually, said operating means being also arranged to close the auxiliary switch when the main switch is opened electrically and having provision by which the auxiliary switch may be closed manually when main switch is in open position.

In testimony whereof, I have signed my name to this specification.

CHESTER D. AINSWORTH.
